UNITED STATES PATENT OFFICE.

IRA G. LEEK, OF SAN FRANCISCO, CALIFORNIA.

DENTAL ENGINE.

SPECIFICATION forming part of Letters Patent No. 397,990, dated February 19, 1889.

Application filed February 16, 1888. Serial No. 264,235. (No model.)

To all whom it may concern:

Be it known that I, IRA G. LEEK, of the city and county of San Francisco, State of California, have invented an Improvement in Dental Engines; and I hereby declare the following to be a full, clear, and exact description of the same.

My invention relates to the class of dental engines, and especially to the cranes or brackets by which the flexible power-conveyer and hand-piece are suspended from the wall, and may have imparted to them such variety of movement as will adapt the tool or bit carried in the hand-piece to work in any required position with facility.

My invention consists in the constructions and combinations of devices, which I shall hereinafter describe and claim.

The object of my invention is to provide for the proper variety of movement for the hand-piece which will enable the use of the engine in all possible positions.

Referring to the accompanying drawings, Figure 1 is a view of my dental engine. Fig. 2 is a longitudinal section through the sleeve C. Figs. 3 and 4 are longitudinal sections through the arm D at the bearing I. Fig. 5 is a longitudinal section of the arm at its joint.

A is a bracket fixed to the wall B. C is a sleeve, the rear end of which is connected with the bracket by means of the vertical pivot c, so that said sleeve may have a movement in a horizontal plane.

D is the crane-arm, made of a hollow or tubular piece, which is divided into sections united by the hinge d, which permits the sections to be turned to an angle with each other. The rear end of the arm is fitted into the sleeve C and adapted to turn therein, so as to have an axial movement. The connection is rendered secure and the joint controlled by means of a set-screw, c', which presses down a split portion, c², of the sleeve upon the arm within and binds it with more or less force, so that said arm may be made to turn as freely as required.

Into the outer or forward end of the arm D is fitted the sheath E, which incloses the flexible power-conveyer e and carries on its end the hand-piece F, all in the usual manner.

Within the sections of the arm D are the power-transmitting rods G, which at the hinge

or joint d are united by the flexible piece g of coiled wire, so that the sections of the arm may have their movement with relation to each other without interfering with the transmission of the power. It will be observed that the joint at d is made of an open character, so as to avoid any interference, when bending, with the flexible connection g of the power-transmitting rods G. On the rear end of the rear section-rod, G, is a pulley, H, over which the driving-belt h passes, and whereby rotation is imparted through the rods G and flexible power-conveyer e to the chuck of the hand-piece. The rods G are journaled in the tubular arm and kept central by means of bearings I, fixed in the arm by screws i, and which are provided with holes i', communicating with holes i², made in the arm itself, so that the journals may be kept properly oiled.

From the foregoing description it will be seen that the crane-arm D may have three simple movements and several combinations of these, resulting in the most complete adaptation of the engine to all the positions in which it may be necessary to use it. In the first place, the arm may have an axial movement, which will enable it, in connection with the hinge at d, to have its outer section, which carries the hand-piece, turned to any angle in a vertical plane. Then, through the vertical pivot-connection of the sleeve C, the arm may be turned to any point in a horizontal plane, and, in connection with the other movements, the hand-piece may be brought into the most convenient position for working under all circumstances.

By the interposition of the power-transmitting rods G in the tubular arm I am enabled to do away with all the cumbersome external belting which is used in connection with many dental-engine brackets for transmitting the power to the hand-piece chuck. In my machine the belting is only at the rear end and I use but a single pulley, in which respect the machine enjoys all the advantages of simplicity which are to be found in the common engines.

Having thus described my invention, what I claim as new, and desire to secure by Letters Patent, is—

1. In a dental engine, the hand-piece and flexible power-conveyer, in combination with

the fixed bracket, the sleeve connected therewith by a vertical pivot, the arm carrying the hand-piece and conveyer at one end and fitted at the other end in the sleeve and axially rotary therein, and the hinge-joint in the arm, substantially as described.

2. In a dental engine, the hand-piece and the flexible power-conveyer, in combination with the fixed bracket, the vertically-pivoted sleeve, the tubular axially-rotary arm fitted in the sleeve and carrying the hand-piece and power-conveyer, said arm having a hinge-

joint, *d*, the rods *G* within the tubular arm, connected with the power-conveyer at one end and having a pulley at the other end, and the flexible coil or piece connecting the rods at the hinge of the arm, substantially as described. 15

In witness whereof I have hereunto set my hand.

IRA G. LEEK.
